UNITED STATES PATENT OFFICE.

HERMANN SCHULER, OF DUSSELDORF, GERMANY, ASSIGNOR TO RHEINISCHE METALLWAAREN-UND MASCHINENFABRIK, OF DUSSELDORF-DERENDFORF, GERMANY, A CORPORATION OF GERMANY.

GUN FOR HIGH AND LOW ANGLE FIRING.

Application filed November 25, 1924, Serial No. 752,207, and in Germany October 11, 1924.

The invention consists in a gun with barrel recoil and wheeled under carriage which is adapted both for firing at low angles of elevation, for example up to 20 degrees and therefore is suited for low trajectory firing, and also for high angled firing up to the greatest usual angles of elevation, for example up to 75 degrees.

The gun has a high ballistic efficiency and, even when of large calibre, it is light and portable, and is steady under fire. It has for this reason when used with small angles of elevation a low firing position, which is obtained by the use of an axle cranked downwards, on the crank of which the system, pivoted on trunnions provided on the cradle, with the barrel and the front portion of the longitudinally extended under carriage are supported. For use at low angles of elevation, the gun is, therefore, a modern barrel recoil gun with a long trail. The traversing of the gun barrel is effected in the modern well-known manner by lateral displacement of the under carriage resting on the axle. For firing within the low angle of elevation an elevating gear is inserted in known manner between the pivoted system, comprising the barrel, cradle and buffer, and the part of the under carriage which supports it and takes up the recoil. This part is not simply the under carriage, but a special construction, a kind of intermediate carriage, which is arranged between the sides of the main carriage, and when firing at low angles of elevation it maintains its whole length in the same position with respect to the under carriage and, therefore, also a part of this carriage rests constantly on the wheel axle.

This intermediate carriage, which directly carries the pivoted system at low angle fire, is pivoted approximately at the centre of the longitudinal extension of the under carriage. It is itself provided with trunnions about which it may be swung from its position in low angle firing.

For high angle firing the pivoted system is first set to the limiting small angle of elevation, for example 20 degrees, by means of the elevating gear serving for the low trajectory, and then the non-recoiling part, the cradle, is rigidly coupled with the inter-

mediate carriage. The larger angle of elevation is then imparted to the barrel, by the intermediate carriage being swung with the barrel, cradle and buffer in the vertical plane about the trunnions at its rear and mounted in the under carriage. This arrangement ensures, since the intermediate carriage and the cradle are rigidly connected together, that these parts cannot be relatively displaced.

The intermediate carriage is of sufficient length to allow a free recoil of the barrel, even at the greatest elevations, without the provision of any special means for reducing the recoil. The coupling between the cradle carrying the barrel and the intermediate carriage for the high angle firing is provided by the elevating gear for the low angle firing, which is provided with a device of known kind which allows the coupling to be released, in order that the barrel with the cradle can be quickly swung from the firing position into the horizontal loading position, and conversely.

The two front arms of the under carriage, between which is the intermediate carriage, both at low angle firing and also at high angle firing are supported so as to be laterally displaceable on the axle of the carriage. They form, therefore, a constant connection between the axle, which also forms a part of the traversing device, and the rear part of the carriage and the spade attached to the latter, so that both at low angle and at high angle firing the rotation of the under carriage in the horizontal plane about the spade as a pivot imparts the traversing movement to the barrel.

The side plates of the under carriage can be made sufficiently strong to take up the recoil at high angle firing; but in order that the under carriage should be kept as light as possible and also to relieve the carriage axle from stresses, at high angle fire the rear portion of the under carriage is preferably utilized as a platform lying on the ground.

The accompanying drawings represent by way of example two constructions according to my invention.

Figure 1 shows a side elevation of the gun with a transversely divided under car-

riage in the horizontal position of the gun utilized; at the angle of elevation α the barrel;

Figure 2 is a corresponding plan;

Figure 3 is a side elevation of the gun at greater elevation of the barrel in the high angle firing position;

Figure 4 is a side elevation of the gun showing a modified construction with the gun barrel in the horizontal position.

Referring to Figures 1 to 4, the under carriage is divided transversely to its longitudinal dimensions. In transport and when used at low angle firing, the carriage with its long trail is so formed that the part a of the under carriage provided with the spade is continued forward into the side plates b . These plates are connected at c and d rigidly but easily removable with the rear part a of the under carriage by removable bolts which connect eyes b^1 and b^2 of the side plates b with corresponding eyes a^1 and a^2 of the rear part a . At their forward ends they engage by guides b^3 with the cranked carriage axle e and rest on this so as to be transversely displaceable.

Between the side plates b of the under carriage is arranged the intermediate carriage f which consists of two cheeks parallel to the side plates b . It is connected by eyes f^1 at its rear end and corresponding pins with the side walls b so as to be capable of swinging in a vertical plane; the removable bolts of the lower connecting points of the under carriage a^1 engage also in the eyes f^1 of the intermediate carriage. During transport and for low angle fire bolts g are introduced through eyes b^4 at the front ends of the side plates b into corresponding holes f^2 of the cheeks of the intermediate carriage and, therefore, prevent any angular displacement of the intermediate carriage relatively to the under carriage.

The barrel k is guided on the cradle l which contains the buffing and running out gear and is pivoted, by horizontal trunnions m provided at its rear part, at the front part of the intermediate carriage f . On one of the two trunnions m is secured a toothed sector n^1 of the elevating gear for setting the low angle of elevation. The sector n^1 is in engagement with elevating gearing n^2 which is disposed transversely on one cheek of the intermediate carriage f .

On the intermediate carriage there is also mounted the gear o^1 of a second elevating device which is in engagement with the toothed sector o^2 , which is placed on the rear portion of one side plate b of the under carriage. The elevating gear n^1 and n^2 is arranged to elevate the barrel within the angle α shown in Figure 1 which corresponds to the small angles of elevation, for example up to 20 degrees; and for larger angles of elevation within the angle β shown in Figure 3, the second elevating gear (o^1 and o^2) is

utilized. At the angle of elevation α the breech of the gun barrel in the rear end position of its recoil comes close to the ground and the direction of the recoil stresses passes approximately through the eye c of the intermediate carriage f into the under carriage.

For the higher angles of elevation the barrel is first raised to the limiting value (α) of low angle firing and then by the gear o^1 — o^2 the barrel with the cradle and buffer is rigidly coupled in this position with the intermediate carriage f through the elevating gear n^1 and n^2 , and is further elevated about the pivoting pins at the points c of the under carriage.

In order to allow this pivoting movement of the system which has been previously rigidly connected with the under carriage, the forward connection of the intermediate carriage f with the side plates b of the under carriage is released by drawing out the bolts g from the holes f^2 of the intermediate carriage. Also, in order to relieve the axle e and the side plates b of the under carriage from the recoil stresses at high angle fire, the connection between the front and the rear part of the under carriage is released, and the latter is then utilized as a platform lying on the ground for the system comprising the barrel, cradle with buffing device, and intermediate carriage.

The intermediate carriage f with the eyes f^1 at its rear end and the lower eyes b^1 of the side plates b , is connected at the upper eyes a^2 to the rear portion of the under carriage which lies flat on the ground. The eyes f^1 for the pins of the intermediate carriage and the side plates b maintain approximately the position which they had at low angle firing, and the elevation of the barrel is not altered. The system comprising the barrel and the cradle with the buffer and intermediate carriage can be swung by means of the elevating gear o^1 to o^2 about the pins of the so formed new connecting places c (Figure 3).

Wedge members h which are connected at high angle fire at the connecting points c to the eyes b^2 , the side plates b and eyes o^3 on the part a of the under carriage form a rigid connection between the side plates b and the part a . These wedge members h serve at low angle firing to rigidly connect, independently of the side plates b , the intermediate carriage f with the rear part a of the under carriage and for this purpose their eyes are connected to the points c and d and at i to the under carriage. Since the centre of gravity of the system pivoted about the trunnions both at low angle and at high angle firing lies considerably before this pivot, compensating devices are provided which relieve the elevating gear from the pressure of the pivoted masses.

The fine traversing adjustment is imparted to the gun by a traversing gear, which is not shown in the drawing, and which in known manner laterally displaces the carriage on the carriage axle.

The elevating gear n^1 to n^2 for low angles of elevation, which for high angle fire rigidly couples the cradle with the intermediate carriage f , is provided with a known device, which is not shown and which allows this coupling to be released so that the barrel with the cradle can be rapidly swung from the firing position into the horizontal loading position, and conversely.

In the modification shown in Figure 4 the under carriage consists of two undivided side plates a which rest at their front ends in the manner previously described on the cranked carriage axle e so as to be laterally displaceable. At their rear part they are bent downwards, so that a large portion of the under carriage in the firing position acts as a platform resting on the ground.

The gun barrel k is guided on the cradle l which by its horizontal trunnions n during transport and at low angle firing is pivoted in the bearings a^1 in the front part of the walls of the carriage a . The intermediate carriage f inserted between the barrel and the side plates a at the front eyes f^2 of its side cheeks provide bearings for the trunnions m and is pivoted by the horizontal trunnions f^1 at its rear end in the portion of the under carriage which is bent downwards.

The arrangement and action of the elevating gear is the same as in the construction previously described. In transport and low angle firing the readily withdrawn bolts g are inserted in the bearings a^1 of the plates of the under carriage a . After the bolts g have been drawn out, the barrel can be raised for the large angles of elevation, the system comprising the barrel, cradle and buffer being rigidly coupled by the elevating gear o^1 to o^2 with the intermediate carriage f so that it can be swung upwards about the trunnions f^1 pivoted in the under carriage. The recoil stresses are taken up by the rear portion of the under carriage serving as a platform.

I claim:

1. A high and low angle firing gun comprising an under carriage having a pair of removable side plates extending to a carriage axle; an intermediate carriage associated with said under carriage; a gun pivoted in the intermediate carriage; means on the intermediate carriage for elevating the gun for low angle firing; means on the under carriage for elevating the intermediate carriage and the gun for high angle firing; and means for interconnecting said carriages so that upon high angle firing the under carriage will act as a platform.

2. A high and low angle firing gun com-

prising an under carriage having front and rear parts; a gun pivoted in the carriage; and filling pieces for interconnecting the front and rear parts of the under carriage.

3. A high and low angle firing gun comprising an under carriage having front and rear parts; an intermediate carriage associated with said under carriage; a gun pivoted in the intermediate carriage; and filling pieces connecting the intermediate carriage at low angle firing with the rear part of the under carriage.

4. A high and low angle firing gun comprising an under carriage having front and rear parts; an intermediate carriage associated with said under carriage; a gun pivoted in the intermediate carriage; and filling pieces connecting the rear part of the under carriage at high angle firing with the front part of the under carriage.

5. A high and low angle firing gun comprising an under carriage having front and rear parts; an intermediate carriage associated with said under carriage; a gun pivoted in the intermediate carriage; and filling pieces connecting the front and rear parts of the under carriage together, said pieces being adapted to connect the intermediate carriage with the rear part of the under carriage at low angle firing and to connect the rear part of the under carriage with the front part of the under carriage at high angle firing.

6. A high and low angle firing gun comprising an under carriage having front and rear parts; an intermediate carriage associated with said under carriage; a gun pivoted in the intermediate carriage; means on the intermediate carriage for elevating the gun for low angle firing; means on the under carriage for elevating the intermediate carriage for high angle firing; and filling pieces connecting the front and rear parts of the under carriage together, said pieces being adapted to connect the intermediate carriage with the rear part of the under carriage at low angle firing and to connect the rear part of the under carriage with the front part of the under carriage at high angle firing.

7. A high and low angle firing gun comprising an under carriage having front and rear parts; an intermediate carriage associated with said under carriage; a gun pivoted in the intermediate carriage; a toothed sector and elevating gear associated with the intermediate carriage for elevating the gun for low angle firing; a toothed sector and elevating gear associated with the under carriage for elevating the intermediate carriage for high angle firing; and filling pieces connecting the front and rear parts of the under carriage together, said pieces being adapted to connect the intermediate carriage with the rear part of the under carriage.

carriage at low angle firing and to connect the rear part of the under carriage with the front part of the under carriage at high angle firing.

8. A high and low angle firing gun comprising an under carriage having front and rear parts; an intermediate carriage associated with said under carriage; a gun pivoted in the intermediate carriage; and means adapted to connect the intermediate carriage with the rear part of the under carriage at low angle firing and to connect the rear part of the under carriage with the front part of the under carriage at high angle firing.

9. A high and low angle firing gun comprising an under carriage having front and rear parts; an intermediate carriage associated with said under carriage; a gun pivoted in the intermediate carriage; and means for connecting said carriages so that upon high angle firing the under carriage will act as a platform.

10. A high and low angle firing gun comprising an under carriage having front and rear parts; an intermediate carriage associated with said under carriage; a gun pivoted in the intermediate carriage; and means connecting the front and rear parts of the under carriage together, said means being adapted to connect the intermediate carriage with the rear part of the under carriage at low angle firing and to connect the rear part of the under carriage with the front part of the under carriage at high angle firing, so that upon the high angle firing position the rear under carriage will act as a platform.

11. A high and low angle firing gun comprising an under carriage; an intermediate carriage associated with said under carriage; a gun and cradle pivoted in the intermediate carriage, said cradle comprising the buffering and running out gear for the gun; and an elevating gear for the gun for elevating the gun for low angle firing, said elevating gear forming a coupling between the cradle and the intermediate carriage for high angle firing.

12. A high and low angle firing gun comprising an under carriage having front and rear parts; an intermediate carriage associated with said under carriage; a gun and cradle pivoted in the intermediate carriage, said cradle comprising the buffering and running out gear for the gun; an elevating gear for the gun for elevating the gun for low angle firing, said elevating gear forming a coupling between the cradle and the intermediate carriage for high angle firing; and means connecting the front and rear parts of the under carriage together, said means being adapted to connect the intermediate carriage with the rear part of the under carriage at low angle firing and

to connect the rear part of the under carriage with the front part of the under carriage at high angle firing.

13. A high and low angle firing gun comprising an under carriage having front and rear parts; an intermediate carriage associated with said under carriage; a gun pivoted in the intermediate carriage; an elevating gear for the gun for elevating the gun for low angle firing, said elevating gear forming a coupling between the gun and the intermediate carriage for high angle firing; and means connecting the front and rear parts of the under carriage together, said means being adapted to connect the intermediate carriage with the rear part of the under carriage at low angle firing and to connect the rear part of the under carriage with the front part of the under carriage at high angle firing.

14. A high and low angle firing gun comprising an under carriage having front and rear parts; an intermediate carriage associated with said under carriage; a gun pivoted in the intermediate carriage; means on the under carriage for elevating the intermediate carriage for high angle firing; and means for elevating the gun for low angle firing, said last-named means forming a coupling between the gun and the intermediate carriage for high angle firing.

15. A high and low angle firing gun comprising an under carriage having front and rear parts; an intermediate carriage associated with said under carriage; a gun pivoted in the intermediate carriage; means on the under carriage for elevating the intermediate carriage for high angle firing; means for elevating the gun for low angle firing, said means forming a coupling between the gun and the intermediate carriage for high angle firing; and means connecting the front and rear parts of the under carriage together, said last-named means being adapted to connect the intermediate carriage at low angle firing and to connect the rear part of the under carriage with the front part of the under carriage at high angle firing.

16. A high and low angle firing gun comprising an under carriage having front and rear parts; an intermediate carriage associated with said under carriage; a gun pivoted in the intermediate carriage; an elevating gear on the front part of the under carriage for elevating the intermediate carriage for high angle firing; an elevating gear for elevating the gun for low angle firing, said last-named gear forming a coupling between the gun and the intermediate carriage for high angle firing; and filling pieces connecting the parts of the carriages together, said pieces being adapted to connect the intermediate carriage with the rear part of the under carriage at low angle fir-

ing and to connect the rear part of the under carriage with the front part of the under carriage at high angle firing.

17. A high and low angle firing gun comprising an under carriage having front and rear parts; an intermediate carriage associated with said under carriage; a gun pivoted in the intermediate carriage; and means for connecting the front and rear parts of the under carriage together, said means comprising the pivot point for the intermediate carriage.

18. A high and low angle firing gun comprising an under carriage having front and rear parts; an intermediate carriage pivoted in the under carriage; a gun pivoted in the intermediate carriage; and means for connecting the front and rear parts of the under carriage together, said means comprising

20 the pivot point for the intermediate carriage.

19. A high and low angle firing gun comprising an under carriage having front and rear parts; an intermediate carriage pivoted in the under carriage; a gun pivoted in the intermediate carriage; and means for connecting the front and rear parts of the under carriage together for high angle firing, said means comprising the pivot point for the intermediate carriage.

20. A high and low angle firing gun comprising an under carriage having front and

rear parts; an intermediate carriage pivoted in the under carriage; a gun pivoted in the intermediate carriage; and means for connecting the front and rear parts of the under carriage together for high angle firing, said means comprising the pivot point for the intermediate carriage and being adapted to connect the intermediate carriage with the rear part of the under carriage for 40 low angle firing.

21. A high and low angle firing gun comprising an under carriage having front and rear parts; an intermediate carriage pivoted to the under carriage and in which the gun is pivoted; and means for connecting the front and rear parts of the under carriage together, said means comprising the pivotal connection for the intermediate carriage.

22. A high and low angle firing gun comprising an under carriage having front and rear parts; an intermediate carriage; a gun pivoted in the intermediate carriage; and an interconnection between the parts of the under carriage so that the rear part of the under carriage will act as a platform upon high angle firing, said means forming the pivot point of the intermediate carriage.

In testimony whereof I have affixed my 60 signature.

HERMANN SCHULER.
